UNITED STATES PATENT OFFICE.

LUIGI PAVIA, OF ALLENTOWN, PENNSYLVANIA.

TENSION DEVICE AND THE LIKE.

Application filed June 23, 1926. Serial No. 118,112.

This invention relates to the manufacture of eyeleted shuttle tension levers. These are usually formed from a piece of wire by bending it so as to produce a spiral bearing portion, a shank or body portion projecting from one end of the bearing portion and formed with upstanding loops or eyelets at intervals, and an arm projecting from the other end of the spiral bearing portion and shaped for the attachment thereto of an elastic band for holding the device in proper cooperative relation with other fixed eyelets in the shuttle.

One object is to provide a tension lever of this class which may be manufactured without a certain waste which obtains in the manufacture of such devices as at present practiced.

Another object is to form the said arm of the device so as to facilitate the attachment thereto and removal therefrom of the mentioned elastic.

The drawing shows,

In Fig. 1 the improved tension lever in side elevation; and

In Fig. 2 a section on line 2—2, Fig. 1.

In the drawing, 1 is the spiral bearing portion, 2 generally denotes the shank or body portion projecting from one end of the body portion and formed with the upstanding loops or eyelets 3, and 4 the arm projecting from the other end of the bearing portion. Except for a detail involving the arm and to be described the device follows in shape the conventional tension lever of its class, a single piece of soft iron wire being used to form it and the wire being suitably bent to produce the part 1, the part 2 with its loops or eyelets 3, and the part 4; this entails, it will be observed, a partial twisting of the metal at the bases of the eyelets.

It is very necessary and in fact substantially the invariable custom in the manufacture of these devices to temper the iron wire after the shaping thereof into its ultimate form so as to harden it and thus adapt the device to withstand the wearing action of the silk or other thread thereon where it passes through the eyelets, which action is otherwise found to produce nicks in the wire which cut the thread and thus render the device useless. Heretofore the practice has been to subject the device as a whole to the proper heat for tempering and then suddenly cool it in water. It is known that this

practice results in a considerable waste because the heating and sudden cooling will in a large number of instances produce a warping of the devices resulting in the eyelets being so badly distorted out of position that they cannot be used unless their eyelets are by hand subjected to a correcting treatment, very frequently involving even individual re-positioning of the eyelets one by one if the distortion is such that one or more of the eyelets is out of alignment with the others.

I have sought by this invention to retain the hardening, by tempering, in the devices so as to protect them against the cutting or nicking action of the thread and at the same time to eliminate the mentioned waste incident to the production of these devices, and this I have accomplished in the following way:

I first bend the soft iron wire to the required form shown and then subject it to the tempering operation. But instead of subjecting the device as a whole to the tempering treatment I heat to a tempering heat those portions, exclusively, which undergo cutting or nicking by the thread, and then suddenly cool the wire to temper said portions, which are marked 3^a. In consequence of this treatment I find that when after the heating step in the tempering operation the devices are plunged in cold water to effect the hardening such hardening is not only confined to the portions 3^a, where it is required, but that all of the devices retain their original shapes, as designed, and that no distortion takes place and consequently no correcting treatment is necessary, so that an appreciable economy results in the production. In other words, the tempering treatment being isolated from those parts of the devices which are in a state of strain, especially at the twisted bases of the eyelets, and which tend to assume new positions on changes in temperature, the devices come from the tempering treatment without being mal-formed. As for the article itself there is also the advantage that if any eyelet requires at any time re-positioning as the result of accidental distortion in use this can be accomplished without breaking for the device is tractable to that end in all portions excepting where such bending is not required and where hardness and hence brittleness is present and is required for resisting wear by the thread.

The arm 4 in the conventional device of this class has a plain eye to receive the (rubber) elastic for yieldingly holding the tension lever in a definite position in the shuttle and so as properly to cooperate with the other or fixed guides therein (see my Patent No. 1,439,322, for example). It is a tedious operation to attach the elastic to this eye, requiring first to thread the elastic through the eye and then knot the end of the elastic. To avoid this I provide the end of the arm 4 with an open spiral eye 4^a. In the use of this construction the elastic is first knotted and then entered into the eye by manipulating it in a fashion to cause

it to follow the spiral space existing between the convolutions of the spiral eye.

Having thus fully described my invention what I claim and desire to secure by Letters Patent is:

A tension lever of the class described consisting of a piece of wire bent to include a bearing portion, a shank projecting from said bearing portion and having eyelets projecting therefrom at intervals, and an arm forming one end of the wire and bent into an eye to receive the knotted end of a rubber elastic and formed as an open spiral.

In testimony whereof I affix my signature.

LUIGI PAVIA.
